PRINTING DEVICE

Filed Dec. 4, 1929.

UNITED STATES PATENT OFFICE

VALENTINE J. MOHLER, OF RIVER FOREST, ILLINOIS, ASSIGNOR TO ADDRESSOGRAPH COMPANY, OF WILMINGTON, DELAWARE, A CORPORATION OF DELAWARE

PRINTING DEVICE

Application filed December 4, 1929. Serial No. 411,417.

This invention relates to printing devices of that class which are adapted to be stored in accordance with a card index system and to be run through addressing or other machines for printing. These devices commonly comprise a frame and a plate having printing characters embossed thereon, the frame being provided with retaining means for detachably securing the plate in place thereon. 5

10 The retaining means have comprised overlapping parts of the frame with which opposing edges of the plate are engaged by a full endwise movement of the plate on the frame, and they have also comprised yielding means in 15 the form of locking tongues on the frame arranged to engage one or both ends of the plate for locking the plate on the frame. These locking devices permit the plate to be slid thereover into proper position on the 20 frame but they act as stops engaging the edges of the plate at one or both ends to prevent endwise movement of the plate on the frame after it is properly positioned. To permit removal of the plate from the frame 25 for replacement or other purposes it is necessary to depress one of the locking devices before the plate can be removed. Operators generally use a thumb nail or a finger nail and very often a finger nail file or a knife 30 blade or any other pointed instrument, for depressing the locking device. If this operation is repeated very often it is liable to disfigure the thumb nail or finger nail and if an instrument is used it is very apt to be applied 35 too forcibly with the result that the locking device is deformed and will not return to locking position after the plate is removed as it is intended that it should do. The retaining devices which overlap opposing edges of the 40 plate extend continuously or discontinuously and substantially throughout the length of the plate and more or less effort is required to guide and move the plate into and out of position on the frame. To facilitate this movement it has been customary to make these 45 edges of the plate discontinuous in a sort of scallop but this does not entirely overcome the difficulties of inserting and removing the plate. The insertion and removal of plates 50 is done occasionally by some users while other users employ operators who are constantly engaged in this work and since the plates and frames are manufactured for universal service it is the effort of the manufacturer to simplify the labor of the constant operator 55 without adding to the difficulties of the occasional operator and without lessening the efficiency of the printing device. To enable the plate to slide freely it has been customary to provide a greater clearance between the edges 60 of the plate and the retaining means on the frame than would be necessary merely to permit sliding engagement. With such a clearance the plate is always capable of a limited movement on the frame within the retaining 65 means and while this movement is not ordinarily objectionable so far as printing and registration is concerned it may become undesirable and even objectionable when the clearance is increased by wear of parts and other 70 causes incidental to production manufacture.

It is the object of this invention to overcome the difficulties in the manufacture and use of printing devices above mentioned, and others, to facilitate the insertion of the plate 75 in the frame and removal of the plate from the frame, and to hold the plate rigidly in place in the frame against relative movement.

A further object of the invention is to release the plate from the locking device which 80 holds the plate in the retaining means on the frame by manipulation of the frame independent of or in conjunction with the locking device under pressure of the fingers and without requiring the use of finger nails or instruments of any kind.

Further objects are to enable engagement 85 of the plate with the retaining means and disengagement therefrom by very short sliding movements of the plate on the frame; to enable the plate to be inserted in initial position on the frame by a transverse movement as distinguished from an end to end movement; to permit an especially free movement of the 90 plate in the retaining devices while the plate is being positioned on or removed from the frame to facilitate these operations; and to hold the plate rigidly in place on the frame 95 in its final position.

And a further object is to eliminate the 100

yielding device which has been relied upon heretofore to a large extent for locking the printing plate on the frame and to provide means which operate by wedging action produced by the sliding movement of the plate into position on the frame for holding the plate rigidly in position.

I have illustrated the invention in a selected embodiment in the accompanying drawing and referring thereto,

Fig. 1 is a front view of a printing device with the printing plate in initial insertion position on the frame.

Fig. 2 is a similar view showing a card and a plate in position on the frame.

Fig. 3 is a back view of the frame.

Fig. 4 shows a frame having two plates thereon.

Fig. 5 is a sectional view on the line 5—5 of Fig. 1.

Fig. 6 is a sectional view on the line 6—6 of Fig. 2.

Referring to the drawing the frame 6 is provided with retaining devices 7 for detachably holding an information card 8 thereon. The frame also has retaining devices 9, 9' to receive a printing plate 10. The plate retaining device at the bottom of the frame is preferably in the form of a continuous bead; the retaining devices for engaging the ends of the plate are preferably in the form of overhanging lips as shown in Fig. 5 or they may be ordinary stops as heretofore used; and the retaining devices 9' for retaining the top edge of the plate are preferably in the form of elongated lips or flanges. All of the retaining devices are stamped from the metal sheet from which the frame is formed. The retaining devices 9' are spaced apart and from an intermediate holding device 11 which is also stamped from the frame. The plate has retainer projections 12 on its upper edge to slidably engage the lips 9'. These projections are spaced from the ends of the plate and from each other and between the retainer projections the edge of the plate is crowned at 13, to provide a wedge projection, by inclining the edge upwardly from each retainer projection to a high point located midway between the ends of the plate in the form of the invention illustrated in the drawing. And the retainer projections 12 and the wedge projection 13 are so positioned with respect to the lips 9' and holder 11 that when the lower edge of the plate is inserted in the bead 9 at the bottom of the frame the upper edge of the plate will clear the lips 9' and the holder 11 so that the upper edge of the plate may lie sufficiently close to the body of the frame to permit the projections 12 to engage the lips 9' upon sliding movement of the plate. In the initial position of the plate, Fig. 1, its right end portion lies upon the right end retaining device 9 but this device does not prevent engagement of the re-

tainer projections with the lips as just described. If necessary slight pressure may be applied on the plate at the right end portion to effect engagement of the projection 12 adjacent the right end of the plate with its lip 9'. The projections 12 are of sufficient height to interengage the lips 9' when the plate is in final position, Fig. 2. As the plate is slid to final position the wedge projection 13 comes to rest with a wedging action against the holder 11 whereby the plate is held rigidly in position on the frame. The parts are desirably made to provide the wedging effect to hold the plate in fixed position on the frame but it is recognized that this is a neatness of fit which it is difficult to provide in production manufacture and to preserve in continued use and while this accuracy of fit is desirable it is not absolutely essential for the invention. The retaining devices 9 engaging the ends of the plate act as stops to prevent endwise movement of the plate on the frame and so long as the projections 12 engage the lips 9' when the lower edge of the plate is engaged with the bead 9, and the holder 11 cooperating with the wedge projection 13 prevents transverse movement of the plate sufficient to permit disengagement of the plate from the lips 9' or the bead 9, the plate will be held on the frame even though it may be capable of a slight movement relative to the frame. The frame is preferably made from the blank more fully described in my co-pending application Serial No. 411,416, filed December 4, 1929, and it has at each end a plurality of slots 14 formed by striking up the retaining stop devices 9 from the body of the frame. The spacing flanges reinforce and strengthen the frame transversely but the slots being alined tend to weaken the frame longitudinally at the end portions. This makes it possible for the operator to bend the end portion of the frame, as shown in Fig. 5, to clear the end retaining stop 9 from the plate so that it can be easily moved endwise from its final position, Fig. 2, to its initial position, Fig. 1, for removal. The complete removal is effected by slightly swinging the upper edge of the plate forward until it has cleared the lips 9' and holder 11 and then lifting the plate out of the bead 9 at the bottom of the frame. And it may be observed here that a simple way of inserting the plate in the frame is to arrange it about the position indicated in Fig. 1 and then inserting the lower edge of the plate into the bead and flattening the plate against the frame to the position shown in Fig. 1. Ordinarily bending of the end of the frame for removal of the plate, as described, will not damage the frame but it is appreciated that the bending may be carried too far and damage the frame and therefore to cause the plate to clear the end retaining device stop 9 by a very slight bending movement of the end

portion of the frame one or more yielding pressure sections 16 are provided in the plate section of the frame which can be operated by finger pressure to lift the end portion of the plate. The pressure section may be conveniently made by cutting part of a circle 16' in the frame. The pressure section may be operated alone to lift the end of the plate sufficiently to clear the stop 9, or the end of the frame may be bent to accomplish this result without operating the pressure section, but it is desirable that they be used conjointly because it facilitates the removal operation. I also prefer to make the frames and the plates so that the plates can be inserted or removed from either end, and this is the way I have shown them in the drawing. The edge of the holder which co-operates with the edge projection of the plate is below the base of the lips 9' where they connect with the body of the frame and this makes it necessary to insert the plate by transverse movement into engagement with the bead at the bottom of the frame as shown in Fig. 1 after which the plate is moved to the left into position on the frame. It will be found convenient in removing a plate from a frame to press down on the right hand end of the frame with the thumb of the right hand and at the same time press upward upon the adjacent pressure section with the forefinger of the right hand until the plate is clear of the retaining stop at the right end of the plate, and substantially at the same time slide the plate by pressure of the thumb of the left hand to the right until it can be grasped by the thumb and forefinger of the right hand and lifted away from the frame. These printing devices can be used interchangeably with old printing devices and the plates can be used in old printing devices but the old plates cannot be used in the new frames because they are not constructed to cooperate with the retaining and holding devices of the frame. The wedge projection on the plate cooperates with the holder 11 to hold the plate in a fixed position on the frame and prevents undesired movement thereof during use of the device. The invention simplifies the construction of the printing device and also simplifies and facilitates the insertion and removal of plates without damage to the frame nor injury to the operator. The invention can be embodied in printing devices having two plates 17 and 18, Fig. 4, arranged one above another upon the frame 19. In this construction lips 20 are employed as the equivalent for the bead to engage the lower edge of the plate 17 and the pressure sections 21 are made of sufficient size and are located to overlap sections of both plates, thereby enabling them to be operated for the removal of either or both plates as desired.

I have shown the invention in selected embodiments which are sufficient for this appli-

cation but I realize that changes in the form, construction and arrangement of parts may be necessary to adapt the invention to other types of printing devices which are or may be required to meet the demands of business and I reserve the right to make all such changes within the scope of the following claims.

I claim:

1. A printing device of the class described comprising a frame, a printing plate having type characters thereon, means for detachably retaining the plate on the frame, said means comprising a device on the frame engaging an end of the plate, and a yielding pressure section on the frame back of the plate adjacent said end thereof adapted to be operated to lift said end of the plate sufficiently to clear said retaining device and permit removal of the plate from the frame.

2. A printing device of the class described comprising a frame, a printing plate having type characters thereon, means for detachably retaining the plate on the frame, said means comprising a device on the frame engaging an end of the plate, and a yielding pressure section on the frame back of the plate and adjacent said end thereof, the end of the frame being bodily and yieldingly bendable and said pressure section adapted to be operated to release the plate from said retaining device and permit removal of the plate from the frame.

3. A printing device of the class described comprising a frame, a printing plate having type characters thereon, said frame having a spacing flange at one end and on its back, means for detachably retaining the plate on the frame and including a retaining device adjacent said flange and projecting above the front face of the body of the frame to engage an edge of the plate, and means for moving the plate to release it from said retaining device to permit removal of the plate from the frame.

4. A printing device of the class described comprising a frame, a printing plate having type characters thereon, means for detachably retaining the plate on the frame and including means overlapping portions of the top and bottom edges of the plate and also including means abutting the end edges of the plate, a wedge projection on one edge of the plate, and means on the frame cooperating with said wedge projection for holding the plate in a fixed position in the retaining devices on the frame.

5. A printing device of the class described comprising a frame, a printing plate having type characters thereon, means for detachably retaining the plate on the frame, said plate having retainer projections spaced apart on its upper edge and a wedge projection between said retainer projections, said retaining means overlapping said projections

- and portions of the bottom edge of the plate and abutting the end edges of the plate, and means on the frame cooperating with said wedge projection for holding the plate in a fixed position in the retaining devices on the frame.
6. A printing device of the class described comprising a frame, a printing plate having type characters thereon, retaining means for detachably retaining the plate on the frame, said plate having retainer projections spaced apart on its top edge and a wedge projection between said retainer projections, and a holder on the frame cooperating with said wedge projection for holding the plate in a fixed position in the retaining means on the frame, the retaining means which engage the top edge of the plate being spaced apart to permit the bottom edge of the plate to be engaged with its retaining means by a transverse movement of the plate and said projections to be engaged with the retaining devices therefor by an endwise movement of the plate.
- 25 7. A printing device of the class described comprising a frame, a printing plate having type characters thereon, means for detachably retaining the plate on the frame, said means comprising a device on the frame forming a stop at one end of the plate, and a yielding pressure section formed by cutting the frame, said pressure section being located back of the plate and opposite said stop and adapted to be operated to lift the end of the plate sufficiently to clear said stop.
8. A printing device of the class described comprising a frame, a plurality of printing plates having type characters thereon, means for detachably retaining the plates on the frame, said means comprising devices on the frame forming stops for adjacent ends of the plates, and a yielding pressure section on the frame back of and overlapping the plates adjacent said ends thereof and adapted to be operated to lift the ends of the plates sufficiently to clear the stops.
9. A printing device of the class described comprising a frame, a printing plate having type characters thereon and removably mounted on the frame, an upwardly extending stop at an end of the frame against which an end of the plate is abutted, said frame having a plurality of cooperating slots spaced apart and arranged in substantial alignment adjacent the end of the frame to increase the flexibility of the end portion of the frame and enable it to be easily bent to clear the stop from the end of the plate and permit removal thereof from the frame.
- 60 10. A printing device of the class described comprising a frame, a printing plate having type characters thereon, means overlapping top and bottom edges of the plate for retaining the plate on the frame, said plate being freely movable in said overlapping retaining

means, and cooperating means on the frame and on the plate for securing the plate in fixed position on the frame by a wedge effect when the plate is moved in said retaining means to final position on the frame.

76 11. A printing device of the class described comprising a frame, a printing plate having type characters thereon and removably mounted on the frame, and a plurality of stops spaced apart and stamped up on the front of the frame in substantially vertical alignment adjacent an end thereof, one of said stops being abutted by an end of the plate, said stamped stops increasing the flexibility of the frame so that the end portion 75 may be easily and temporarily bent to clear the abutted stop from the end of the plate and permit removal of the plate from the frame.

80 12. A printing device of the class described comprising a frame, a printing plate having type characters thereon and removably mounted on the frame, said frame having a plurality of slits arranged in substantially vertical alignment adjacent an end thereof 85 and the frame being stamped at said slits to form stops spaced apart on the front of the frame, one of said stops being abutted by an end of the plate, said slits and stops increasing the flexibility of the frame so that 90 the end portion may be easily and temporarily bent to clear the abutted stop from the end of the plate and permit removal of the plate from the frame.

95 13. A printing device of the class described comprising a frame, a printing plate having type characters thereon and removably mounted on the frame, and a plurality of stops spaced apart and stamped up from the front of the frame in substantially vertical 100 alignment adjacent an end thereof, one of said stops being arranged to be engaged by an end of the plate, said stamped stops increasing the flexibility of the frame so that the end portion may be easily and 105 temporarily bent to clear the stop from the end of the plate and permit removal of the plate from the frame, and a yielding section in the frame under the plate adapted to be pressed to clear the plate from said stop. 110

115 14. A printing device of the class described comprising a frame, a printing plate having type characters thereon, means on the frame for removably retaining the plate thereon, means for making one end portion of the frame yieldingly bendable under pressure, and said retaining means comprising an upwardly extending member at said yielding portion of the frame adapted to abut the end of the plate under normal conditions and 120 to clear the plate and permit removal thereof from the frame when said end portion is depressed.

125 15. A printing device of the class described comprising a frame, a printing plate having 130

type characters thereon, means on the frame for removably retaining the plate thereon, said frame being weakened at one end portion to permit said end portion to yieldingly bend 5 under pressure, and said retaining means comprising an upwardly extending member on said end portion adapted to abut the end of the plate under normal conditions and to clear the plate and permit removal thereof 10 from the frame when said end portion is depressed.
